FIG. 2.

Inventor
JOHN G. MUELLER,

JOHN G. MUELLER,
By Pauline Paulsen,
Administrator

UNITED STATES PATENT OFFICE

JOHN G. MUELLER, OF DAYTON, OHIO

RAIL BRACE

Application filed June 8, 1928. Serial No. 283,966.

This invention relates to rail braces and is an extension of the invention set forth in Letters Patent No. 1,353,412, issued to me September 21, 1920.

5 It is the object of the present invention to provide a rail brace which can be readily adjusted to position the rails to the desired gauge and to positively retain them in fixed lateral relation with each other.

10 The invention shown and described in said patent disclosed a form of rail brace and clamp equally adaptable to the different weights in steel rails and the variation of dimensions in rail joint construction.

15 The object of the present invention is to provide other constructions for accomplishing the same result which will be efficient, strong and durable, wherein the upper faces of the rail base are engaged by the binding 20 or wedging blocks forming a part of the rail brace and adapted to be interposed between the clamping members of the brace and the rail.

25 In the accompanying drawings Figure 1 is a side elevation, partly in section, of my invention illustrating the brace as applied to the opposite rails of a track.

Figure 2 is a partial side elevation and sectional view of a modified form of my brace.

30 Referring to Figure 1 of the drawings, I have shown the usual track arrangement of two parallel rails 1 and 2 with one form of my improved brace applied thereto. A tie rod 3 extends between and underneath the 35 rails and projects beyond the outside of said rails. The ends of the rod 3 are screw-threaded, as at 4, to a point well inside the rails to permit of applying clamping members 5 on both sides of the base flange of each 40 rail.

45 Coacting with each clamping member 5 is a wedge or binding member 6 having a surface 7 adapted to engage the upper face of the rail base and a downwardly extending portion or heel 7^a with a relatively straight edge 8 to engage the edge of the rail base. The clamping member 5 has a groove formed in its inclined surface for the purpose of providing a guideway 10 to receive the inclined 50 bearing surface 9 of the wedging member

6, whereby as the clamping members are urged by nuts 11 on the tie rod toward the rail the intervening binding or wedging members will be pressed inward against the edge of the rail base and downward on top of the 55 rail base to clamp it. In this way it will be seen that both the clamping members and the wedging members are adjusted simultaneously and the wedging member maintained in its correct relation to the rail and prevented 60 from lateral movement.

The clamping members 5 are provided with apertures 12 to receive the tie rod 3, and these apertures are of such size as to provide for adjustment of the members 5 to adapt 65 the clamp to different weight rails. It will be understood, therefore, that the rail brace and the clamp used in connection therewith may be made in a standard size equally adaptable to all sizes or weights of rails, or, where 70 the braces are used in connection with structures other than track construction the clamps are adaptable to a considerable variation of dimensions of the parts to be clamped.

75 The relation of the members 5 and 6 when applied to the rails by reason of the coacting angular surfaces 9 and 10 is that of the binding wedge and clamp in their effect upon the flange of the rail, the flange being positively gripped above and below and on the edges 80 thereof when the clamp is drawn to position on the tie rod.

In Figure 1, I have shown the relative position of the clamping members and wedging or binding members when applied to medium 85 weight rails, but it will be understood that when applied to other weight rails the wedging member will occupy the same relative position to the rail, the clamping members merely being a greater or lesser distance 90 apart.

Referring to the modified form of construction shown in Figure 2, clamping members 13 are mounted on a tie rod 14, nuts 15 serving to hold the clamping members in 95 adjusted position. Coacting with the clamping members 13 are wedging or binding members 16 and 17, the binding member 16 serving to engage the upper face of the rail base as also the web thereof to brace them and hav- 100

ing a depending or heel portion 18 with an inner engaging surface 19. The binding member 17 is carried by the tie rod 14 along with the clamping members 13 and has a flat portion 20 adapted to engage the bottom of the rail base and a heel portion 21 having a straight edge 22 adapted to engage the edge of the rail base. Each clamping member 13 has a groove formed in each of its inclined surfaces for the purpose of providing guideways 23 and 26 to receive respectively the inclined bearing surface 23 of the wedging member 16 and the inclined bearing surface 24 of the wedging member 17 so that as the clamping members are urged toward the rail by the nuts 15 the wedging members will be forced against the rail to brace it and will be maintained in correct relation to the rail and the clamping members. It will also be observed that the engaging surface 19 of the heel on the wedging member 16 is adapted to contact with the outer surface of the heel 21 on the binding member 17, whereby as the clamping members are urged toward the rail the wedging member 16 will be pressed inward and downward and the wedging member 17 inward and upward thereby effecting the bracing of the rail flange above and below and on the edges thereof, as well as the web of the rail.

From the foregoing description it will be apparent that I have provided a brace adaptable to rails of varying dimensions without any change in construction, which will effectively brace the rails in fixed lateral relation with each other.

It will be understood that I desire to comprehend within my invention such modifications as may be necessary to adapt it to varying conditions and uses.

Having thus fully described my invention, what I claim as new and desire to secure by Letters Patent, is:

1. In a railroad rail brace, the combination with a threaded tie rod, of clamping members mounted on said rod and adapted to be urged by nuts on the rod toward a rail between them, binding members mounted on said tie rod, each having a portion projecting above the top of the rail base, and other binding members located above the tie rod and fitted between said clamping members and the upper face of the rail base and each having a projecting portion fashioned to fit about the projecting portion of the first mentioned binding members, said clamping members being fashioned to engage the several binding members to urge them against the top, edges and bottom of the rail base.

2. In a railroad rail brace, wedge members adapted to engage the underside and edges of a rail base, second wedge members located above the tie rod and adapted to fit about part of said first wedge members

and engage the top of the base flanges of the rail, and means to force said wedge members into engagement with the rail.

3. In a railroad rail brace, wedge members adapted to engage the underside and edges of a rail base, second wedge members located above the tie rod and adapted to fit about the upper part of said first wedge members and engage said rail, and means to force said wedge members into engagement with the rail.

4. In a railroad rail brace, in combination with a tie rod, wedge members adapted to engage the underside and edges of a rail base, second wedge members located above the tie rod and adapted to fit about the upper part of said first wedge members and engage the rail, and clamp means on said rod adapted to engage said wedge members to hold them in engagement with the rail.

5. In a railroad rail brace, in combination with a tie rod, wedge members on said rod adapted to engage the underside and edges of a rail base, second wedge members located above the tie rod and adapted to fit about part of said first wedge members and engage the rail, and clamp means on said rod adapted to engage said wedge members to hold them in engagement with the rail.

6. In a railroad rail brace, in combination with a tie rod, wedge members adapted to engage the underside and edges of a rail base, second wedge members located above the tie rod and adapted to fit about the upper part of said first wedge members and engage the upper part of the base flange and the web of the rail, clamp means on said rod, and means on said rod to force said clamp means into engagement with said wedge members to grip the rail.

In testimony whereof, I affix my signature.

JOHN G. MUELLER.
